Patented Aug. 22, 1967

208,372

COMBINED REGISTER AND DRYING RACK

William S. Spangle, 627 Orchard Hill Drive,
Pittsburgh, Pa. 15238

Filed Oct. 20, 1965, Ser. No. 87,608

Term of patent 3½ years

(Cl. D49—1)

Fig. 1

Fig. 2

Fig. 3

FIG. 1 is a front, elevational view of a combined register and drying rack showing my new design;

FIG. 2 is a side view thereof; and,

FIG. 3 is a perspective view thereof showing the end portions of the rack seated in their sockets.

I claim:

The ornamental design for a combined register and drying rack, substantially as shown and described.
